[57] CLAIM

The ornamental design for a remote receiver, as shown and described.

DESCRIPTION

FIG. 1 is a front view of a remote receiver showing the preferred embodiment of my new design;

FIG. 2 is a right side elevational view thereof;

FIG. 3 is a bottom view thereof;

FIG. 4 is a top view thereof;

FIG. 5 is a rear view thereof; and,

FIG. 6 is a left side elevational view thereof.

The cord of the remote receiver in FIGS. 1-2 and 5-6 is shown broken away to indicate indeterminate length.
